UNITED STATES PATENT OFFICE.

HOMER TIPTON MCGILL, OF STUTTGART, ARKANSAS.

APPARATUS FOR POLISHING GRAIN.

Application filed April 28, 1924. Serial No. 709,621.

To all whom it may concern:

Be it known that I, HOMER TIPTON MCGILL, a citizen of the United States, and a resident of Stuttgart, in the county of Arkansas and State of Arkansas, have invented certain new and useful Improvements in Apparatus for Polishing Grain, of which the following is a specification.

This invention relates to an apparatus for 10 polishing rice and is of the type known in the trade as a "brush".

The object of the invention is to provide an apparatus of this character wherein the entire mass of rice undergoing the polishing 15 operation is subjected to the cooling action of currents of air to maintain a uniform and proper temperature throughout the entire polishing space whereby to prevent checking or cracking of the grains of rice.

Another object is to provide an apparatus of this character embodying a novel brush assembly, and a novel polishing drum assembly as well as a novel housing and foraminous casing which greatly facilitate 25 the changing of the brushes of the polishing drum to vary the character of the polishing action as well as to facilitate the replacement of worn brushes.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view, showing one embodiment of the apparatus;

Figure 2 is a view thereof in transverse vertical section, on line 2-2 of Figure 3;

Figure 2^a is a view similar to Figure 2 but showing the lower portion or base of the apparatus;

Figure 3 is a view in horizontal section, on line 3-3 of Figure 2;

Figure 4 is a view in horizontal section, on line 4-4 of Figure 2;

Figure 5 is a fragmentary perspective view, illustrating the collector for the polished grain;

Figure 6 is a similar view, showing the collector for the polish;

Figure 7 is a group view in perspective, 55 showing the brush construction employed; and

Figure 8 is an enlarged fragmentary view in horizontal section, showing certain of the details of the housing.

Referring to the drawings wherein for the sake of illustration is shown one embodiment of the invention, it will be seen that the apparatus comprises a housing designated generally at 10 and including a plurality of vertical channel bars 11 secured at their lower ends to base pieces 12. The upper ends of the channel bars 11 are fastened to a depending annular flange 13 integrally formed with a top plate 14. An annular bottom plate 15 is also provided and has a marginal flange 16 fastened to the channels 11. The body portion of the housing 10 is made up of a number of imperforate sections 17 which take the form of sections of a cylinder. Each section 17 is designed to fill the space between the adjacent flanges of adjacent channels 11. Each vertical edge of each section 17 has secured thereto a packing strip 18 (see Figure 8), and each packing strip 18 has a bent back edge 19 adapted to extend around the flange of the adjacent panel. Packing 20 is inserted between the bent back edge 19 and the flange of the adjacent channel.

Readily releasable means is provided for holding the sections 17 in assembly with the strips 18 having their edges compressing the packing 20. This means includes a number of bolts 21 adjustably fastened by nuts 22 to the body portion of each channel 11, as shown to advantage in Figure 8. A locking bar 23 is mounted on each bolt 21, each locking bar 23 being formed with an opening midway its length which provides for a sliding fit of the locking bar on its bolt 21. When the locking bar extends transversely of the channel 11 its ends are engageable with the bent back edges 19 of the packing strips 18 whereas when the locking bar extends or is positioned so as to lie substantially lengthwise of the channel member 11, it is accommodated in the channel of such member and is not engageable with the edges 19. A hand operated cam 24 is pivotally connected to the outer end of each bolt 21 and coacts with the locking bar 23 mounted on the bolt to force the locking bar into engagement with the edges 19 of the packing strips 18 to compress the packing 20 and hold the sections 17 in assembly. These cam members 24 may also be readily swung to released position illustrated in dotted

lines in Figure 8 to permit the sections 17 of the housing to be removed.

A rotary polishing drum of cylindrical form and designated generally at 25 is mounted within the housing 10. The drum 25 includes an upper end plate 26 and a lower end plate 27, the end plates 26 and 27 having annular flanges 28 and 29 to which longitudinally extending and circumferentially spaced channel bars 30 are fastened, these channel bars 30 making up the body portion of the drum. As shown in the drawing, the end plates 26 and 27 are of annular form so that the drum has its ends open and since the body portion of the drum is made up of the spaced channel bars 30 the periphery of the drum is also formed with openings extending from end to end thereof. The upper end plate 26 of the drum is formed with a neck 31 surrounding its opening and this neck 31 is journaled in a bearing 32 provided therefor in the top 14 of the housing 10. The lower end plate 27 of the drum is connected to a sleeve shaft 33 by a spider designated generally at 34 and having a hub 35 fixed to the sleeve shaft 33 and having arms or blades 36 integral therewith or otherwise secured thereto and serving to connect the hub 35 with the end plate 27 of the drum. Thus the spider 34 serves to support the drum as well as to transmit motion thereto. The arms 36 of the spider are flat and elongated and are twisted or curved so as to serve as blades of a fan for forcing air in through the adjacent end of the drum 25. The portion of the sleeve shaft 33 adjacent the spider 34 is mounted in a combined radial and thrust bearing 38 mounted by arms 39 on the channel bars 11. The lower end of the sleeve shaft 33 has a pulley 40 fixed thereto, as shown in Figure 2^a and this pulley is rotatably mounted in a step bearing 41 designed to take radial and thrust loads. The pulley 40 is driven from a belt 42 from any suitable or convenient source of power.

The channel bars 30 of the drum open outwardly and to these channels a novel brush assembly designated generally at 45 and constituting an important feature of the present invention is applied. Each brush assembly includes a carrier 46 preferably in the form of an elongated strip, rectangular in cross section and designed to snugly fit in any of the channels of the channel bars 30. To each carrier 46 a cushioned leather brush 47, such as is widely employed in the art, is attached, as at 48. Releasable fastening devices are provided for securing each carrier 46 to the channel bar 30 with which it is associated, and preferably these fastening devices comprise bolts 49 mounted on the carrier 46 and adapted to be accommodated in bolt holes 50 provided therefor in the channel bars 30. Nuts 51 are threaded

on the bolts 49 and coat with the channel bars 30 to hold the carrier in the channels of the bars 30. These nuts 51 may be readily removed to permit the entire brush assembly to be taken from the drum in the event the brush assembly becomes worn or in the event it is desirable to replace the brush assembly with another of different dimensions to enable variation in the polishing action to be had.

A foraminous casing designated generally at 55 is arranged within the housing 10 and encircles the polishing drum in spaced relation thereto to define the polishing space. This casing 55 includes a sectional skeleton frame and wire mesh 57 applied to the inner sides of the sections of the skeleton frame 56. The sections of the skeleton frame are detachably connected to permit of easy assembly and disassembly to enable access to be had to the polishing drum. The upper end of the skeleton frame 56 is secured by releasable fastening devices to a depending annular flange 58 provided on the top plate 14 and the lower end of the skeleton frame 56 rests on the bottom plate 15 of the housing 10.

The rice to be polished is fed in through the top plate 14 by the hopper or chute 60 and passes down between the foraminous casing 55 and the rotating drum 25 wherein the rice is polished in the usual manner by the action of the brushes 45 and the foraminous casing 55. After having been polished the rice falls into a collector designated generally at 61 and comprising a cylindrical outer shell 62, a conical inner shell 63 and V-shaped deflectors 64 arranged between the shells and insuring the delivery of the grain to the offtake conduits 65.

Due to the polishing action it has been found that the rice is heated up to some extent and as a consequence checks or cracks whereby its value is very materially reduced. In order to maintain the entire mass of the rice being polished at a constant, uniform and proper temperature it is proposed to cause air currents to traverse and pass through every unit of area of the mass of rice being polished in such a novel and effective manner that the desired cooling action is had without in any way interfering with the polishing operation. To this end a fan shaft 70 is provided and is extended axially through the polishing drum, as shown in Figure 2. The upper portion of the shaft 70 is journaled in a bearing bracket 71 and the lower portion of this shaft extends through the sleeve shaft 33 and is so fitted in the sleeve shaft as to be freely rotatable with respect thereto. At its upper end the shaft 70 has fixed thereto a pulley 73 driven by a belt 75 from any suitable source of power. The fan shaft 70 is to be driven in a direction opposite to that in which the

drum 25 is driven. Within the drum 25 and adjacent the ends thereof spiders 76 are fixed to the fan shaft 70. The spiders 76 have radially extending arms 77, and to these arms 77 fan blades 78 are secured. These blades 78 are flat and elongated and extend for substantially the full length of the drum. With this arrangement a fan is provided within the drum and is effective to force air out through the drum at all points around and along the same.

When the fan shaft 70 is rotated, the fan blades 78 act as a centrifugal fan and cause the air to be forced outwardly between the channel bars 30 along the entire length of the drum. Thus the air from the fan flows between the brushes 45 and through every unit of area of the mass of grain being polished so that all of the grain is uniformly cooled and maintained at a constant and proper temperature to prevent checking or cracking of the same. The currents of air thus set up pass through the foraminous casing 55 and into the space between this casing and the housing 10. During its travel through the grain the air entrains the polish, dust and the like, and this is also carried into the space between the foraminous casing and the housing. In order to prevent excessive pressures from building up in the housing and to control the escape of the polish, dust or the like the housing is formed with a plurality of air exits which preferably are of rectangular form and extend vertically of the housing for the greater portion of its length. By providing air exits which extend for substantially the full length of the housing, the proper distribution of the air currents through the mass of grain being polished is insured. The air exits are designated at 80, and in each air exit a framing 81 may be inserted and suitably secured. The framing 81 carries a panel 82 of cloth or suitable foraminous material having a texture permitting the passage of air therethrough while resisting the passage of dust, polish or other fine particles contained in the air. In fact it has been found that when the fan is turned at a relatively slow speed so as to set up relatively slow moving air currents, the panel of cloth is sufficient to precipitate the polish, dust or the like. However, it may be desirable at all times and it is especially desirable at high fan speeds to provide a hood 83 for each air exit. The hoods 83 have openings encompassing the air exits and these hoods have apertured ears 84 whereby they may be readily fastened by screws, bolts or the like to the exterior of the housing. Pipes 85 lead from the lower portions of the hoods to the point where the polish is to be discharged.

At slow fan speeds practically all of the polish is precipitated in the space between the foraminous casing 55 and the housing

10, and even at high fan speeds, the whirling currents of air striking the inner surface of the housing and eddying therefrom and into the air exits provide for a substantial precipitation of the polish. The polish thus precipitated is gathered in a polish collector 90 and is carried by pipes 91 to the bins or sacking machines. The polish collector 90 is shown to advantage in Figure 6 and includes an outer shell 92, an inner shell 93 and V-shaped guides 94 disposed between the shells 92 and 93 and insuring delivery of the polish to the pipes 91.

In order to insure escape of the air from the housing 10 at high fan speeds auxiliary air collectors designated generally at 100 may be employed. When assembled with the inner side of the housing, as shown in Figure 3 these auxiliary air collectors provide substantially tubular casings 101 of curved form and each having one end offset as at 102 and communicating with the adjacent air exit, the opposite end of each casing being open, as indicated at 103. The inner wall of each casing 101 has lips 103 struck outwardly therefrom so that air enters the end of the casing and also through the vents or ports adjacent each lip 103. These air collectors 100 may be provided at the top of the housing 10, as illustrated in the drawing and may also be provided adjacent the bottom as well as intermediate the top and bottom if found desirable.

In operation the rice is fed in through the hopper 60 and is distributed by the rotating upper end plate 26 of the polishing drum and by the upper portions of the brushes 45 so that the entire polishing space which is defined by the polishing drum 25 and the foraminous casing 55 contains the mass of rice being polished. The character of the brushing action may be readily varied as found desirable. For instance light brushing may be effected by a large feed and by employing brush assemblies having narrow strips of wool and leather or by slowing up the rotary movement of the polishing drum. Hard or heavy brushing can be done by a small feed in conjunction with a speeding up of the drum and the employment of brush assemblies having wide leather. A variety of finishes however can be made by changing the feed only from small to large but the harder the machine brushes the more heat is generated and the more necessary it is to provide for a proper cooling action to prevent changes in temperature and consequent checking of the grains of rice. Under all conditions the present invention provides for the circulation through the entire mass of grain being polished of cooling currents of air. In this connection the location of the fan within the drum is believed to be an important feature for with such an arrangement the air is positively forced outwardly

through the entire mass of grain being polished and cannot flow around the grain as it would if it were permitted to follow the path of least resistance. Moreover the fan blades extend the entire length of the drum and cause current of air to flow through every unit of area of the mass of grain being polished. The fan blades 78 act as the blades of a centrifugal fan and their action in forcing the air outwardly through the drum and across the mass of grain is supplemented by the action of elongated air deflectors 110 having an extent approximately equal to the extent of the channel bars 30 making up the periphery of the drum and bolted to the inner surfaces of these channel bars. The air deflectors 110 have pointed wings 111 which extend angularly from the angle bars in the direction of rotation of the drum so that they positively force or deflect the air currents set up by the blades of the fan 78 through the spaces between the channel bars 30 and outwardly through the brushes 45. The whirling currents of air thus generated by the blades of the fan and thus evenly distributed around and along the polishing drum traverses the entire mass of grain being polished, and this uniform and wide distribution of the air currents is enhanced by the fact that the air exits extend the full length of the housing 10 and are provided at a number of points around the housing.

The sections of the housing may be readily removed and the foraminous casing may be readily taken apart to provide for access to the polishing drum. The brush assemblies on the polishing drum may be taken therefrom and replaced by new brushes or by brushes of different dimensions with the expenditure of minimum time and labor. This is an important feature since it avoids shutting down the brush for a considerable length of time when it is necessary to replace the brushes of the polishing drum. Both the rice and the polish are carried away as fast as the polishing action proceeds by virtue of the provision of the collectors 61 and 90, respectively.

It is to be understood that the speed of the fan may be varied as desired although under ordinary conditions the speed of the fan ranges from 800 to 1200 R. P. M. At slow fan speeds the hoods 83 need not be used since the screens or cloths 82 confine the polish while permitting the escape of air.

It is to be understood that although the fan shaft may be rotated in a direction opposite to that in which the drum rotates, the fan shaft may also be rotated in the same direction as the drum, the air deflectors being modified or omitted if found desirable.

I claim:

1. In an apparatus of the character described, a hollow rotary polishing drum of

open formation, a fan operating within the drum for forcing air outwardly therethrough, and means independent of the fan for forcing air into one end of said drum.

2. In an apparatus of the character described, a hollow rotary polishing drum of open formation, a foraminous casing encircling the drum to define a polishing space, polishing pads carried by the drum and co-operable with the foraminous casing, a fan operating within the drum for forcing air across the polishing space, and air deflectors carried by the drum and projecting inwardly thereto for directing the currents of air generated by the fan outwardly through the openings of the drum.

3. In an apparatus of the character described, a hollow rotary polishing drum having openings in its periphery and in its ends, a rotary cylinder shaft, spider arms connecting the shaft and one end of said drum, said arms being twisted so as to force air into the interior of said drum and a fan operating within said drum for forcing air outwardly through the peripheral openings of the drum.

4. In an apparatus of the character described a hollow rotary polishing drum having openings in its periphery and at its ends, a foraminous casing encircling the drum in spaced relation to define a polishing space, a fan arranged within the drum for drawing air in through the ends of the drum and forcing the air through the peripheral openings of the drum and across the polishing space throughout its extent, and a housing for the drum and casing, said housing having air exits extending lengthwise thereof, and means associated with the air exits for controlling the escape of dust, polish or the like.

5. In an apparatus of the character described, a polishing drum having longitudinal channels, and brushes including carrier strips designed to be received in said channels, readily releasable fastening devices for securing the carrier strips to said channels, and cushioned leathers attached to said carrier strips.

6. In an apparatus of the character described, a polishing drum, brushes including carriers, readily releasable fastening devices securing the carriers to the drum, and cushioned leathers attached to said carriers.

7. In an apparatus of the character described, a polishing drum, brushes including carriers releasably secured to the drum, cushioned leathers attached to said carriers, a foraminous casing for said drum made up of detachably connected sections and a housing for the casing and drum, said housing including vertical channels, removable sections extending between the channels, packing strips secured to the sections and having bent back edges extending around the

flanges of the channels, packing between the bent back edges and the flanges of the channel, and readily releasable means cooperable with the channels and with the bent back edges of the packing strips for compressing the packing and holding the removable sections in position.

8. In an apparatus of the character described, a polishing drum, brushes including carriers releasably secured to the drum, cushioned leathers attached to said carriers, a foraminous casing for said drum made up of detachably connected sections and a housing for the casing and drum, said housing including vertical channels, removable sections extending between the channels, packing strips secured to the sections and having bent back edges extending around the flanges of the channels, packing between the bent back edges and the flanges of the channel, and readily releasable means cooperable with the channels and with the bent back edges of the packing strips for compressing the packing and holding the removable sections in position, said readily releasable means including bolts secured to the channels, locking bars slidably mounted on bolts and engageable with the packing strips, and locking cams pivotally connected to the bolts and cooperable with the locking bars.

9. In an apparatus of the character described, a hollow rotary polishing drum having openings in its periphery and at its ends, a foraminous casing encircling the drum in spaced relation to define a polishing space, a fan arranged within the drum for drawing air in through the ends of the drum and forcing the air through the peripheral openings of the drum and across the polishing space throughout its extent, and a housing for the drum and casing, said housing having air exits extending lengthwise thereof, and means associated with the air exits for controlling the escape of dust, polish or the like, said means including cloth screens extending across said exits, and hoods surrounding the outside of the air exits and leading therefrom.

10. In an apparatus of the character described, a hollow rotary polishing drum having openings in its periphery and at its ends, a foraminous casing encircling the drum in spaced relation to define a polishing space, a fan arranged within the drum for drawing air in through the ends of the drum and forcing the air through the peripheral openings of the drum and across the polishing space throughout its extent, a housing for the drum and casing, said housing having air exits extending lengthwise thereof, and means associated with the air exits for controlling the escape of dust, polish or the like, said means including cloth screens extending across said exits.

11. In an apparatus of the character described, a hollow rotary polishing drum having openings in its periphery and at its ends, a foraminous casing encircling the drum in spaced relation to define a polishing space, a fan arranged within the drum for drawing air in through the ends of the drum and forcing the air through the peripheral openings of the drum and across the polishing space throughout its extent, 70 a housing for the drum and casing, said housing having air exits extending lengthwise thereof, means associated with the air exits for controlling the escape of dust, polish or the like, said means including hoods surrounding the outside of the air exits and leading therefrom.

12. In an apparatus of the character described, a hollow rotary polishing drum having openings in its periphery and at its ends, a foraminous casing encircling the drum in spaced relation to define a polishing space, a fan arranged within the drum for drawing air in through the ends of the drum and forcing the air through the peripheral openings of the drum and across the polishing space throughout its extent, 85 a housing for the drum and casing, said housing having air exits extending lengthwise thereof, and means associated with the air exits for controlling the escape of dust, polish or the like, said means including auxiliary air collectors arranged in said housing and leading to said air exits.

13. In an apparatus of the character described, a hollow rotary polishing drum having openings in its periphery and at its ends, a foraminous casing encircling the drum in spaced relation to define a polishing space, a fan arranged within the drum for drawing air in through the ends of the drum and 90 forcing the air through the peripheral openings of the drum and across the polishing space throughout its extent, a housing for the drum and casing, said housing having air exits extending lengthwise thereof, 95 and means associated with the air exits for controlling the escape of dust, polish or the like, auxiliary air collectors arranged in said housing and leading to said air exits, each auxiliary air collector comprising a curved 100 tubular casing having one end connected to said air exit and having its other end open, the inner wall of the casing having deflecting lips struck outwardly therefrom.

14. In an apparatus of the character described, a hollow rotary polishing drum having openings in its periphery and at its ends, a foraminous casing encircling the drum in spaced relation to define a polishing space, a fan arranged within the drum for drawing air in through the ends of the drum and 110 forcing the air through the peripheral openings of the drum and across the polishing space throughout its extent, and a housing 115 for the drum and casing, said housing having 120

ing air exits extending lengthwise thereof, means associated with the air exits for controlling the escape of dust, polish or the like, a grain collector below the polishing space, and a polish collector below the space defined by the foraminous casing and the housing.

15. In an apparatus of the character described, a hollow rotary polishing drum comprising end plates and a plurality of longitudinal channel bars secured to the end plates and circumferentially spaced from each other, a brush carried by each channel bar, a fan shaft extending axially through the rotary drum, a plurality of flat elongated longitudinally extending blades carried by the fan shaft, and elongated air deflectors carried by the channel bars of the drum.
16. In a rice polishing apparatus, a hollow rotary polishing drum having openings in its periphery and at its ends, a foraminous casing encircling the drum in spaced relation thereto to define a polishing space, means for causing cooling currents of air to travel

erse the polishing space including a fan operating within the drum for drawing air in through the ends of the drum and forcing the air through the peripheral openings of the drum and across the polishing space throughout its extent, driving mechanism for the drum, and means independent of the driving mechanism and of the drum for rotating the fan.

17. In an apparatus of the character described, a hollow rotary polishing drum having openings in its periphery and at its ends, a foraminous casing encircling the drum in spaced relation thereto to define a polishing space, means for causing cooling currents of air to traverse the polishing space comprising a fan shaft extending axially through the drum and beyond the ends thereof, fan blades carried by said shaft, and means cooperating with said shaft for rotating the same, a sleeve shaft loosely mounted on said fan shaft, spider arms connecting the sleeve shaft and the drum, and means for rotating said sleeve.

HOMER TIPTON McGILL.
